UNITED STATES PATENT OFFICE

EVERETT G. EARNHARDT, OF MOUNT CARMEL, PENNSYLVANIA

LIGHTNING THROW-OFF DEVICE

Application filed July 23, 1928. Serial No. 294,661.

This invention relates to a lightning throw-off device for high tension lines, the general object of the invention being to provide means for causing the lightning to leave the conductor or line and to dissipate itself in a number of trough-shaped members formed of wire mesh, and one of which is grounded, thereby preventing the bolt of lightning from damaging the insulators which connect the line with its supporting means and from damaging the generators, the transformers and other machinery associated with the line.

Another object of the invention is to so form the hangers which support the line from the towers that said hangers will not interfere with the passage of the lightning along the line, thus preventing the lightning from injuring the insulators and associated parts which connect the hangers with the tower.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a view showing the invention in use.

Figure 2 is a section on line 2—2 of Figure 1.

Figure 3 is a view of one of the breaker members composed of woven wire and showing the insulators for supporting the member from the tower and also showing a portion of a rod which forms a path for the bolt from the shield to the breaker.

Figure 4 is a side view of the grounded wire mesh member.

Figure 5 is an end view thereof.

Figure 6 is an elevation, partly in section, of the assembly which acts to divert the lightning from the line.

Figure 7 is a section on line 7—7 of Figure 6.

Figure 8 is a view of one of the hangers.

Figure 9 is a section on line 9—9 of Figure 8.

Figure 10 is a view of a modified form of hanger.

Figure 11 is a view of the preferred way of supporting the line from a tower.

In these drawings, the numeral 1 indicates the main line which conducts the high tension current from one point to another, and 2 indicates the branch line which is connected with one terminal of the line 1 by the wire 3, this line 2 leading to the power house or to the point of distribution of the current, or this line 2 may be a line which connects two of the lines 1 together. A tower 4 is arranged adjacent the terminal of the line 1 and a tension bar 5 is connected intermediate its ends with the top of the tower by the string of insulators 6, and the lower end of the bar is connected to the top of a tower 7 by a string of insulators 8. The line 2 is also connected with the lower end of the bar 5, as shown at 9, and the line 1 is connected with the top of the bar 5, as shown at 10. A shield 11, of non-conducting material, is formed with a centrally located socket 12 into which the upper end of the bar 5 extends so that the shield is supported from the bar and the line 1 is connected with the lower part of the shield, as shown at 13. This shield is formed to provide a pair of parallel troughs 14 which extend longitudinally of the shield and it is also formed with a depending apron 15 which extends along one side of the bar.

A breaker or lightning dissipating member 16 is supported by the insulators 17 from the top of the tower 4, the body of this member being formed of wire mesh and is of trough shape with its ends tapering downwardly and outwardly and with the edges of said end parts bent over to form the outwardly extending flanges 17'. The body is fastened to a base 18 which is formed with the divergent arms 19, and this base is connected with the insulators 17. A coil spring 20 is fastened to one end of the base and a bar 21 is fastened to this spring, and the other end of the bar is fastened by a spring 22 to an eye bolt 23 which passes through the apron 15 into the upper part of

100

the bar 5. This bar 21 may be formed of glass or other non-conducting material and it may also be formed of arc shape, with its concaved face uppermost. As shown, the 5 ends of the bar 21 are located adjacent one end of the member 16 and one end of the shield 11.

A member 16', formed similar to the member 16, except that it is pointed on but one end, is supported by an extension 24 on the top 10 of the tower, this member 16' being spaced from the member 16 and the end of the member 16' which is farthest from the member 16 is grounded, as shown at 25.

The hangers 26, for supporting the line 1 15 from the towers 27, are preferably formed as shown in Figure 8, which shows a frame 26' formed of two sections, this frame being of substantially ring shape with its bottom portion bent upwardly into the ring, as shown at 20 26'', with the lower ends of the two sections acting as a clamp to hold the fastener 28 which engages the line 1. The top part of the hanger is formed with the lug 28' to which the string of insulators 29 is connected, this 25 string being also connected with the top of the tower, as shown.

Figure 11 shows two of these hangers in use, with the strings of insulators converging upwardly and fastened to a clip 30 which is connected to the top of the tower. This arrangement forms a semi-tension device for supporting the line from the tower.

Figure 10 shows a modified form of hanger, in which I use an inverted U-shaped member 31, the bight of which is connected with the string of insulators, and the lower ends of which are connected together by a cross bar 32 which carries the supporting means 33 for the line 1. It will be seen that in both forms 35 of hangers, the line 1 is supported in a large opening formed by the hanger, so that there are no obstructions for the passage of the lightning over the line, as my theory is that the lightning travels in the form of a ball 40 along the top of the line.

From the foregoing, assuming that my theory is correct, it will be seen that the ball 45 of lightning will travel along the line 1, passing through the hangers without being obstructed by said hangers until it strikes the shield 11 which acts to cause the lightning to pass from the line over the top of the shield on to the bar 21 over which it passes into the member 16. This member, being formed of woven wire, acts to break up or dissipate the bolt and then the lightning jumps the gap 50 between the member 16 and the member 16', and this member 16' acts to further dissipate the lightning and then whatever remains of the bolt passes to ground over the wire 25.

Thus I have provided means for taking a bolt of lightning from a high tension line and dissipating the same without causing a "flash", thereby preventing the lightning from damaging the line and its supporting

means and the machinery in the power house and the distributing means. The apron 25 acts to prevent the current from the line 1 following the lightning across the bar 21.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. A lightning throw-off device for high 80 tension lines comprising a pair of towers, a vertically arranged tension bar, a string of insulators connecting the lower end of the bar with the upper end of one tower, a string of insulators connecting the bar intermediate 85 its ends with the top of the other tower, a shield of non-conducting material supported on the top of the bar, means for connecting one end of the line to the top of the bar, a branch line connected with the bottom of the bar, a top line connecting the two lines together, means for connecting the bottom of the shield to the main line, lightning dissipating means carried by one tower and a member connected with such means and with 90 the bar and forming a path from the shield to such means.

2. A lightning throw-off device for high 95 tension lines comprising a pair of towers, a vertically arranged tension bar, a string of insulators connecting the lower end of the bar with the upper end of one tower, a string of insulators connecting the bar intermediate 100 its ends with the top of the other tower, a shield of non-conducting material supported on the top of the bar, means for connecting one end of the line to the top of the bar, a branch line connected with the bottom of the bar, a top line connecting the two lines together, means for connecting the bottom of 105 the shield to the main line, lightning dissipating means carried by one tower, a member connected with such means and with the bar and forming a path from the shield to such means, such means comprising a number of channel-shaped members formed of wire mesh and spaced apart, the member farthest from the shield being grounded and means for insulating the other member from the tower.

3. A lightning throw-off device for high 110 tension lines comprising a pair of towers, a vertically arranged tension bar, a string of insulators connecting the lower end of the bar with the upper end of one tower, a string of insulators connecting the bar intermediate 115 its ends with the top of the other tower, a shield of non-conducting material supported on the top of the bar, means for connecting one end of the line to the top of the bar, a 120 member connected with such means and with the bar and forming a path from the shield to such means, such means comprising a number of channel-shaped members formed of wire mesh and spaced apart, the member farthest from the shield being grounded and means for insulating the other member from the tower.

125

branch line connected with the bottom of the bar, a top line connecting the two lines together, means for connecting the bottom of the shield to the main line, lightning dissipating means carried by one tower, a member connected with such means and with the bar and forming a path from the shield to such means, said members having downwardly and outwardly tapering ends, with the edges of the end parts turned over to provide outwardly extending flanges.

4. A lightning throw-off device for high tension lines comprising a pair of towers, a vertically arranged tension bar, a string of insulators connecting the lower end of the bar with the upper end of one tower, a string of insulators connecting the bar intermediate its ends with the top of the other tower, a shield of non-conducting material supported on the top of the bar, means for connecting one end of the line to the top of the bar, a branch line connected with the bottom of the bar, a top line connecting the two lines together, means for connecting the bottom of the shield to the main line, lightning dissipating means carried by one tower, a member yieldably connected with such means and with the bar and forming a path from the shield to such means and a depending apron on the shield between the bar and the yieldably supported member.

In testimony whereof I affix my signature.
EVERETT G. EARNHARDT.
